PORTRABLE POWER DRIVEN RECIPROCATING HAND SAW

Harold S. Forsberg, Stratford, Conn., assignor of one-third to Lillian Virginia Volo, Orange, one-third to Natalie Anne Forsberg, and one-third to Bernice Hildegarde Streff, Stratford, Conn.

Application December 9, 1957, Serial No. 48,842

Term of patent 7 years

(Cl. D93—3)

Fig. 1 is a front perspective view of a portable power driven reciprocating hand saw, showing my new design;
Fig. 2 is a side elevation;
Fig. 3 is a front elevation;
Fig. 4 is a rear elevation; and
Fig. 5 is a top plan view.

I claim:
The ornamental design for a portable power driven reciprocating hand saw, substantially as shown.
